UNITED STATES PATENT OFFICE.

FREDERICK C. MEHNERT, OF GOSHEN, INDIANA.

FOLDER AND PUNCHER.

SPECIFICATION forming part of Letters Patent No. 536,037, dated March 19, 1895.

Application filed July 18, 1894. Serial No. 517,920. (No model.)

To all whom it may concern:

Be it known that I, FREDERICK C. MEHNERT, of Goshen, in the county of Elkhart and State of Indiana, have invented a new and Improved 5 Folder and Puncher, of which the following is a full, clear, and exact description.

My invention relates to improvements in that class of devices which are used for folding blank book sections and for punching 10 holes in them preparatory to binding; and the object of my invention is to produce a very simple machine of this kind which is adapted to simultaneously fold the sections and punch the holes therein, which does the work very 15 rapidly, which makes the holes all alike, and which does the work better than the machines in ordinary use.

To these ends my invention consists of certain features of construction and combinations of parts, which will be hereinafter described and claimed.

Reference is to be had to the accompanying drawings, forming a part of this specification in which similar figures of reference indicate 25 corresponding parts in all the views.

Figure 1 is a broken perspective view of the machine embodying my invention. Fig. 2 is a plan view of the machine with the folding arm removed. Fig. 3 is a cross section on the 30 line 3—3 of Fig. 2. Fig. 4 is a broken front elevation of the machine with the folding arm raised. Fig. 5 is a similar view, but with the arm depressed so as to fold a section of a blank or other book; and Fig. 6 is a detail cross section of the folding jaws.

The machine is provided with a suitable table 10 which is supported on a standard 11, the latter resting on feet or legs 12, and projecting through the table near the back part 40 is a shaft 13 which is normally pressed upward by springs 14 and 15, the former being coiled around the shaft and the latter being secured to the table 10 and to a hook 16 projecting from a collar on the shaft, and the upward movement of the shaft is limited by a 45 collar 17 beneath the table. The shaft is prevented from turning by a guide arm 18 which projects through a slot in the standard 11, as shown in Fig. 3. The shaft, at its lower end, 50 has an adjustable connection by means of a screw 19 with a stirrup 20 which supports a treadle 21, this being fulcrumed on one of the

legs 12 and by depressing the treadle the shaft is depressed. The movement of the shaft is limited by a hand screw 23 in the top of the keeper 22 in which the treadle moves. To the upper end of the shaft 13 is fastened the sleeve 24 which carries the folder arm 25, this projecting laterally from the shaft, and the arm is split on the under side to receive the folding blade 26 which projects beneath the shaft. and is provided, at necessary points, with depending spurs or needles 27 which are adapted to pierce the book sections as they are folded, and thus make holes for the binding thread. 65

The folding blade, when depressed, enters the adjustable paper slot formed between the parallel opposed jaws 29 which are mounted in a recess 28 in the table top 10, the angular wear plates 30 covering the tops and inner 70 sides of the jaws and projecting outward so as to form supporting flanges which rest on the table top. The cushions 31 of rubber are arranged between the wear plates and the jaws, and the bolts 32 connect the opposite jaws 75 and provide means by which the distance between the jaws may be regulated. Beneath the jaws is a supporting plate 33 which is held in keepers 34 on the under side of the table and is supported on thumb bolts 35. 80 This arrangement forms a sufficiently strong support for the jaws and enables them to be easily removed when desired.

Behind the paper slot is a gage bar 36 which is arranged at right angles thereto and is provided with a central bend 37 to receive the shaft 13, and the bar has also rearwardly-extending arms 38 which are slotted to receive the thumb screws 39 by which it is fastened to the table 10 and thus the bar may be adjusted backward and forward to suit leaves of different lengths. The table has also fastened to it a side gage 40 against which the side edges of the leaves to be folded are placed, and this gage is held by a screw 41 which may 95 be fastened in either of the holes 42 of the table, as circumstances may require.

In using the machine, the operator places the leaves to be folded and punched on the table top, and pushes them back over the 100 paper slot until their ends strike the gage bar 36 and one edge rests against the gage 40, and then the treadle is stepped on, thus bringing down the folder arm 25 and the blade 26 strik-

ing the leaves, forces their middle parts down into the paper slot, as shown in Fig. 5, thus making a tight smooth fold, while at the same time the spurs or needles 27 pierce the paper 5 and make holes to receive the binding thread.

Having thus described my invention, I claim as new and desire to secure by Letters Patent—

1. A folder and perforator comprising a table provided with a paper slot, of a non-cutting folder blade provided on its lower dull edge with depending needles to perforate or puncture the paper at the fold for the binding thread, substantially as described.
- 15 2. A folder and puncher comprising a table provided in its top with parallel stationary jaws spaced apart to form the paper slot and adjustable toward and from each other to vary the width of the slot, and a depressible folder blade to enter the slot and provided on its lower non-cutting edge with projecting needles or perforating spurs to perforate the paper in the fold for the binding thread without cutting the sheets in two, substantially as 25 shown and described.
3. A folder and puncher comprising a slotted table top, a support on the under side of the table at the said slot, parallel jaws resting on said support, spaced apart to form the paper 30 slot and adjustable toward and from each other to vary the width of said slot, and the vertically reciprocating folder blade to enter the paper slot and provided on its lower non-cutting edge with needles or perforating spurs, 35 to perforate the paper in the fold for the bind-

ing thread, substantially as shown and described.

4. A folder and puncher comprising a slotted table top, parallel spaced jaws adjustable toward and from each other in the table slot, 40 cushioned wear plates at the inner adjacent faces of the jaws and the folder blade adapted to enter the paper slot between the jaws, substantially as shown and described.

5. In a machine of the kind described, the 45 combination, with the slotted table top, of the supporting plate held beneath the slot, and the adjustably connected and oppositely arranged jaws in the table slot, and angular wear plates cushioned on the jaws so as to 50 cover their top and inner edges and rest on the table top, substantially as described.

6. The combination with the table top and its slot, the parallel spaced jaws adjustable toward and from each other in said slot, the 55 vertically reciprocating shaft projecting through the table, a folder blade mounted on the shaft to enter the paper slot formed between said jaws, of the gage bar secured to the table top at right angles to the jaws and 60 adjustable toward and from the jaws; the said gage having transverse slots in its ends receiving set screws and having a bow 37 in its middle to straddle the shaft, substantially as shown and described.

FREDERICK C. MEHNERT.
